UNITED STATES PATENT OFFICE.

DAVID A. EBINGER, OF COLUMBUS, OHIO, ASSIGNOR TO THE COLUMBUS HEATING & VENTILATING COMPANY, OF COLUMBUS, OHIO, A CORPORATION OF OHIO.

LATRINE-CLOSET.

No. 889,917.

Specification of Letters Patent.

Patented June 9, 1908.

Application filed May 18, 1907. Serial No. 374,463.

To all whom it may concern:

Be it known that I, DAVID A. EBINGER, citizen of the United States, residing at Columbus, in the county of Franklin and State of Ohio, have invented certain new and useful Improvements in Latrine-Closets, of which the following is a specification.

My invention relates to latrine closets and has for its object the provision of a device of this character particularly adapted for use in schools, hotels or other public places and constructed in such manner that an efficient ventilation may be had and also constructed in such manner that an efficient flushing may be had.

Further objects and advantages of the invention will be set forth in the detailed description which now follows.

In the accompanying drawing: Figure 1 is a view partly in elevation and partly in section of a latrine closet constructed in accordance with the invention, Fig. 2 is a transverse vertical section upon line $x-x$ of Fig. 1, upon an enlarged scale, and, Fig. 3 is a plan view of the conduit of the latrine closet with the closet seat removed.

Like numerals designate corresponding parts in all of the figures of the drawing.

Referring to the drawing, the numerals 5 designate conduits arranged upon either side of a central partition 6. A plurality of seats 7 which are provided with covers 8 are arranged over these conduits and these seats are separated from each other by partitions 9. A discharge pipe 10 leads from the conduits 5 at one end and a water inlet pipe 11 is connected to the conduit at the opposite end thereof. This inlet pipe is connected to a casing 12 in which buckets illustrated in dotted lines at 13, are pivoted upon a shaft 14. A water supply pipe 15 leads to the casing 12 and when one of the buckets 13 has become filled, it automatically over-balances itself and turns over, bringing the other bucket in position to be filled from the pipe 15 and dumping the contents of the bucket that was filled, into the pipe 11 from whence it passes to the conduit 5.

A plurality of troughs 16 are arranged 50 along the sides of the conduits 5. The walls of these troughs which lie close to the walls of the conduit, are lower than the other walls of said troughs. Water supplied to these troughs consequently overflows and runs 55 down the sides of the conduits, thereby main-

taining a constant flushing of the side walls of these conduits.

As is best illustrated in Fig. 1, the bottom wall of the conduits is formed with a sudden depression 17 and a gradually rising portion 17'. The water flowing through this conduit therefore, is suddenly accelerated as it enters the bowl of each individual closet. Air conduits 18 are connected by ports 19 at the rear of each of the closets and a vent pipe 20 leads from these air conduits to the atmosphere. The water flowing into the sudden depression 17, is caused to eddy and whirl about in these depressions thereby producing a better flushing of the depression than would be the case if the walls upon each side of the depression were formed at the same inclination.

Since the arrangement of closets upon each side of the partition 6 is exactly the same, a description of the arrangement upon one side thereof, will suffice.

A water supply pipe 21 is arranged along the front of the conduit (see Fig. 3) and air inlet openings 22 are formed through the front wall of this conduit to admit air to said conduit. This air is drawn through the openings 22 and ports 19 to the conduits 18 and from thence to the vent pipe 20. Transverse pipes 23 extend from the pipe 21 through the openings 22 and are provided with nozzles 24 which discharge into the trough 16.

By referring to Fig. 3, it will be seen that each individual closet has individual troughs. 90 Shields 25 are arranged over the openings 22. The pipe 21 receives its supply from the casing 12 and is connected to said casing by a short branch pipe 26. When the buckets are turning over, a certain amount of water is spilled into said casing and a certain amount of water runs from the pipe 15 during the turning over of the buckets, to the lower portion of the casing 12. This water runs through the pipe 21 to the troughs 16 and is there utilized to flush the sides of the conduits.

From the foregoing description, it will be seen that simple and efficient means are herein provided for accomplishing the objects of the invention, but while the elements shown and described are well adapted to serve the purpose for which they are intended, it is to be understood that the invention is not limited to the precise construction set 110

forth, but includes within its purview such changes as may be made within the scope of the appended claims.

What I claim is:

- 5 1. A latrine closet comprising a conduit, individual overflowing troughs arranged adjacent each closet, means for supplying water to said troughs, and means for flushing the main conduit, the means for supplying water to the trough comprising a longitudinally extending main pipe and transverse branch pipes, the latter pipes discharging into the troughs.
- 10 2. A latrine closet comprising a conduit, individual overflowing troughs arranged adjacent each closet, means for supplying water to said troughs, means for flushing the main conduit, an air conduit to which all of the closets are connected, and a vent pipe leading from said conduit, the means for supplying water to the trough comprising a longitudinally extending main pipe and transverse branch pipes the latter pipes discharging into the troughs.
- 15 3. A latrine closet comprising a conduit having its bottom provided with a sudden depression which terminates in a gradual rise beneath each of the closets.
- 20 4. A latrine closet comprising a conduit

having its bottom provided with a sudden 30 depression which terminates in a gradual rise beneath each of the closets, and means for flushing said conduit.

5. A latrine closet comprising a conduit having its bottom provided with a sudden 35 depression which terminates in a gradual rise beneath each of the closets, means for flushing said conduit, individual overflowed troughs arranged along the sides of the conduit adjacent each of the closets, and means 40 for supplying water to said troughs.

6. A latrine closet comprising a conduit having its bottom provided with a sudden depression which terminates in a gradual rise beneath each of the closets, means for 45 flushing said conduit, individual overflowed troughs arranged along the sides of the conduit adjacent each of the closets, means for supplying water to said troughs, an air conduit to which each of the closets is connected, 50 and a vent pipe leading from said air conduit.

In testimony whereof I affix my signature in presence of two witnesses.

DAVID A. EBINGER.
